US00D332575S

United States Patent [19]

Redfield et al.

[11] Patent Number: Des. 332,575
[45] Date of Patent: ** Jan. 19, 1993

[54] ELECTRONIC TEST SET FOR
TELECOMMUNICATIONS, ALARM
SYSTEM, AND CIRCUIT TESTING

[75] Inventors: **John M. Redfield**, Brier; **David M. Rollins**, Monroe; **Clay A. Stocklin**, Redmond; **Wayne R. Fukahara**, Seattle; **Denis M. Stack**, Bothell, all of Wash.

[73] Assignee: **Leviton Manufacturing Corporation**, Bothell, Wash.

[**] Term: 14 Years

[21] Appl. No.: 751,692

[22] Filed: Aug. 29, 1991

[52] U.S. Cl. D10/78

[57] CLAIM

The ornamental design for an electronic test set for telecommunications, alarm system, and circuit testing, as shown and described.

DESCRIPTION

FIG. 1 is a front elevational view of a electronic test set for telecommunications, alarm system and circuit testing showing our new design;

FIG. 2 is a right side elevational view;

FIG. 3 is a rear elevational view;

FIG. 4 is a left side elevational view;

FIG. 5 is a top plan view; and,

FIG. 6 is a bottom plan view thereof.

FIG.1
